UNITED STATES PATENT OFFICE.

JOHN E. MITCHELL, OF ST. LOUIS, MISSOURI.

COTTON EXTRACTING AND CLEANING MACHINE.

1,129,220.

Specification of Letters Patent. Patented Feb. 23, 1915.

Application filed December 23, 1912. Serial No. 738,156.

To all whom it may concern:

Be it known that I, JOHN E. MITCHELL, a citizen of the United States, residing in the city of St. Louis and State of Missouri, have invented new and useful Improvements in Cotton Extracting and Cleaning Machines, of which the following is a specification.

This invention relates to cotton extracting and cleaning machines, and has for its object improvements in the machine heretofore patented to me, No. 1,030,913, dated July 2nd, 1912. In the said patented machine the characteristic feature is the employment of double hull boards which regulate the size of openings past the saw cylinder, the upper board allowing the larger, and the lower board the finer pieces of hull to pass through, while the larger pieces are knocked by the saws through the space between the two hull boards. In a pending application of Dennis Parks, Ser. No. 710,391, filed July 19th, 1912, is disclosed an improved boll crushing cylinder, the salient feature of which is the provision of pivoted beaters mounted on a revolving cylinder and traveling within a foraminous inclosure. This construction of boll crusher is shown in the present application, and is used in the commercial machine, manufactured under my patent aforesaid. The advantages of this particular form of boll crusher need not be here recited, but it is sufficient to say that it is deemed essential to the successful operation of the machine. It has been found, however, in practice that with the boll crusher rotating at a rate of speed sufficient to crush and disintegrate the average character of cotton bolls without pulverizing the hulls thereof, a great many bolls of a tough and substantially non-brittle character will not be broken up by the boll crusher, and hence will not be acted on by the saws, and will accumulate in the agitating chamber adjacent to the saws; or else have their cotton extracted, and pass out of the machine, only after relatively long continued action by the saws. It has further been found that if the speed of the boll crusher is increased so that the pivoted arms thereon will strike these tough bolls with sufficient force to disintegrate them, the hulls of the dry bolls will be practically pulverized, rendering the separation of fine

particles thereof from the cotton very difficult. 55

It is one of the purposes of the present invention, therefore, to produce a machine which will provide for crushing, and separating cotton from, bolls which have not been crushed by the boll crusher in the initial operation. 60

To this end the invention consists in this regard in locating a guard adjacent to one of the rotary members confining, in part, 65 the agitating chamber, the guard being located in sufficiently close proximity to the member to insure that a boll passing between it and such rotary member will be crushed. 70

In thus providing for reducing the bolls and larger pieces of hull that have escaped the action of the crusher, I obviate the necessity for the employment of the double hull board principle, for the reason that the hulls are all reduced by the supplemental crushing means to more or less of a uniform size; or at least to such size that the provision of one opening past the saw cylinder is found sufficient, as this opening may 80 be made large enough to permit all the pieces of hull to escape, while substantially preventing the escape of cotton. It inevitably follows, however, that with an ordinary stationary hull board some cotton will 85 escape along with the hulls, and a further purpose of the present invention, therefore, is the provision of means for insuring the engagement of the cotton by the teeth of the saws so as to prevent the escape of the 90 cotton. Various means may be employed for this purpose, that shown in the drawing, and hereinafter described, being a very efficient one; but in all cases the underlying principle consists in forcibly projecting the 95 material about to pass by the saws from the lower end of the hull board into engagement with the saws so that the teeth thereof will engage the cotton while the hulls will be permitted to fall through. 100

With the above stated purposes in view the invention consists essentially in a cotton extracting and cleaning machine comprising feeding and crushing mechanism, a rotary saw cylinder, a rotary pod expeller co-operating therewith, a supplemental crushing roll and co-operating guard, and a vibratory hull board co-operating with the saw cylinder. 105

A vibratory hull board has been demonstrated in practice to effectively prevent the escape of the cotton past the saw cylinder, and it is herein specifically claimed; but 5 I desire it to be understood that it is also used herein as illustrating the broad idea of forcibly projecting the cotton at the lower end of the hull board against the saw cylinder as it is about to fall past the same.

10 The invention is illustrated in the accompanying drawing, in which—

Figure 1 is a central cross sectional view through a machine of the type described constructed according to my present invention, only sufficient of the driving means being indicated to make the operation clear; and Fig. 2 is a broken plan view showing a portion of the saw cylinder and of the vibratory hull board.

15 Referring now to the drawings, 1 indicates the casing of the machine, and 2 a pair of feed rolls mounted on shafts 3, and revolving toward each other, as indicated by the arrows. Each of these rolls is provided 20 around its circumference with longitudinally-extending channel bars 4 which form gripping surfaces to engage the cotton and force it down into the machine.

25 The numeral 5 indicates the combined feeding and boll-crushing cylinder, which is mounted on a shaft 6 and revolves in the direction indicated by the arrows. Partially surrounding the lower side of this cylinder is a screen 7 secured at its ends to 30 cross bars 8, and being preferably provided with several flat faces, as indicated at 9. The cylinder 5 is provided with pivoted beater-arms 10 which coöperate with the flat sides of the screen 7 to crush and 35 disintegrate the bolls.

40 The numeral 11 indicates the saw cylinder, 12 the pod-expeller, and 13 the doffer-brush, all of these parts being substantially the same as illustrated in my patent before mentioned, and not requiring, therefore, further description. In place of the hull boards shown in said patent, however, I employ the construction now to be described.

45 The space 14 between the saw cylinder and the boll crusher forms an agitating chamber into which the cotton and bolls to be treated are discharged by the action of the beater-arms 10. The numeral 15 indicates generally a vibratory hull board, which, in effect, forms the bottom of this 50 agitating chamber. Said hull board is conveniently constructed as follows: Extending substantially from side to side of the machine on the interior thereof is a bar 16 which has secured to its upper side a spring metal plate 17 which is kerfed to provide a series of fingers 18 which extend downward toward the saw cylinder, and at their 55 lower ends are bent downward to form shoulders 19 and inclined portions 20, the lower extremities of which define the size of an opening 21 past the saw cylinder. The width of this opening may vary within reasonable limits, but in practice it would 60 not be less than one-half an inch, nor more than an inch. I have found an opening about three-fourths of an inch in width to be desirable. The bar 16 is secured by one or more hinges 22 to the forward cross 65 bar 8, and has secured centrally of its length an arm 23 having its under side flat and resting upon an agitator 24 secured on a shaft 25, said agitator having alternating flat sides 26 and rounded corners 27. The 70 shaft 25 is driven from a pulley 28 by means of a belt 29. As the agitator 24 revolves it will cause the vibration of the arm 23, as will be readily understood, and this in turn will cause the vibration of the spring 75 fingers 18. The opening between the shoulders 19 and the saw cylinder is sufficiently restricted to prevent the entrance into the space between the inclined portion 20 and the saw cylinder of uncrushed bolls, which 80 latter are taken care of in the manner later to be described. The hulls and cotton, however, passing into such space will be thrown outward by the vibration of the fingers 18, and into engagement with the saw cylinder 85 which will thus insure the engagement of cotton particles thereby, while pieces of hull, not being engaged by the saws, will fall through the opening 21 and thus be finally separated from the cotton. The vibration of the spring fingers 18 is quite 90 rapid, owing to their being constructed of spring metal, and being entirely free from the bar 18 to their lower ends, but the arc 95 of vibration is not great, nor are the cotton 100 and hull particles projected with any considerable force against the saw cylinder, it being only necessary to insure that the cotton particles shall be thrown with such force as to cause them to be engaged by the 105 teeth of the saws and thus prevent their escape past the saw cylinder.

In order to provide for crushing bolls which have not been reduced by the action 110 of the boll crusher 5 I employ the following construction: Mounted above and slightly to one side of the pod expeller 12 is a supplemental crushing roll 30 which may be of the same size and construction as the pod expeller, and is mounted to rotate with its 115 channel bars in sufficiently close proximity with those of the pod expeller to prevent the passage of any material between them. Extending from side to side of the machine and mounted in the ends thereof is a circular bar 31 which I term a guard, the said 120 guard being located substantially in the same horizontal plane as the axis of the pod expeller 12, and being located sufficiently close to the crushing roll 30 that any 125 130

5 pods passing between the guard and said crushing roll will be crushed by the channel bars 32 thereof. The uncrushed bolls entering the agitating chamber and falling into the bottom thereof will be stopped by engagement with the shoulders 19 and the teeth of the saws, which latter throw them upward; and while this action may be repeated a number of times, the bolls will 10 sooner or later pass upward into the space between the pod expeller 12 and the guard 31 and through the action of the crushing roll 30 will be forced against said guard and thereby crushed, after which they fall 15 back into the agitating chamber to be again acted on by the saws. The crushing roll 30 and guard 31 not only serve to crush bolls, but they likewise will break up larger pieces of hull so that all of the hulls are broken 20 up into sufficiently small pieces to permit them to readily pass through the opening 21.

In practice I find that a machine constructed according to my present invention will operate to thoroughly and rapidly 25 clean the cotton so that the same will be discharged through the opening 33 by the doffer brush practically entirely free from hull particles and other refuse matter, and is then in the ideal condition to be ginned. 30 In practice the cleaned cotton is delivered by a suitable conduit, (not shown), directly to the gin as it passes through the opening 33. The hull particles and other refuse, of course, fall to the bottom of the 35 casing, whence they are conveyed out of the machine by an endless screw conveyer 34, operated by a pulley 35 from the belt 29. The feed rolls 2, boll-crushing cylinder 5, pod expeller 12, saw cylinder 11, doffer- 40 brush 13, and crushing roll 30 are rotated in the directions respectively indicated by the arrows adjacent thereto by suitable driving mechanism which is of the usual construction, and which, therefore, it is not 45 deemed necessary to more fully illustrate or describe.

I claim:

1. A cotton extracting and cleaning machine comprising a saw cylinder, a hull 50 board, the lower end of which regulates the size of an uninterrupted opening past the saw cylinder for the escape of hulls, and means for forcibly projecting cotton from the lower end of the hull board directly into 55 contact with the saw cylinder.

2. A cotton extracting and cleaning machine comprising a saw cylinder, a hull board directed toward the saw cylinder and having a lower end-portion inclined at a 60 less angle to said cylinder, and defining the size of an uninterrupted opening past the saw cylinder for the escape of hulls, and means for forcibly projecting cotton from the lower end of the hull board directly into 65 contact with the saw cylinder.

3. A cotton extracting and cleaning machine comprising a saw cylinder, a hull board directed toward the saw cylinder and having a lower end-portion inclined at a less angle to said cylinder, the lower termination of the upper part of the hull board lying sufficiently close to the saw cylinder to prevent bolls from passing into the space between the lower end-portion and the saw cylinder, and the lower end of the hull 70 board lying nearer to and regulating the size of an uninterrupted opening past the saw cylinder, and means for forcibly projecting cotton at the lower end of the hull board into contact with the saw cylinder. 75

4. A cotton extracting and cleaning machine comprising crushing and feeding mechanism, a saw cylinder, a pod expeller coöperating therewith, a hull board, the lower end of which regulates the size of an 85 uninterrupted opening past the saw cylinder for the escape of hulls, said hull board, saw cylinder and pod expeller confining, in part, an agitating chamber, and a supplemental crushing member in said agitating 90 chamber.

5. A cotton extracting and cleaning machine comprising crushing and feeding mechanism, a saw cylinder, a pod expeller coöperating therewith, a hull board, the 95 lower end of which regulates the size of an uninterrupted opening past the saw cylinder, said hull board, saw cylinder and pod expeller confining, in part, an agitating chamber, and a supplemental crushing member located in the upper part of the agitating chamber and independent of the saw cylinder. 100

6. A cotton extracting and cleaning machine comprising crushing and feeding 105 mechanism, a saw cylinder, a pod expeller coöperating therewith, a supplemental crushing roll in the upper part of said agitating chamber, a stationary guard coöperating with said crushing roll and between 110 which and said roll the material to be crushed passes, and a hull board, the lower end of which regulates the size of an opening past the saw cylinder.

7. A cotton extracting and cleaning machine comprising crushing and feeding 115 mechanism, a saw cylinder, a pod expeller coöperating therewith, a hull board, the lower end of which regulates the size of an opening past the saw cylinder, said hull 120 board, saw cylinder and pod expeller confining, in part, an agitating chamber, a supplemental crushing member in said agitating chamber, and means for forcibly projecting cotton at the lower end of the hull 125 board into contact with the saw cylinder.

8. A cotton extracting and cleaning machine comprising a saw cylinder, a pod expeller, a crushing roll located adjacent to said pod expeller, a guard located adjacent 130

to said crushing roll and between which and said roll the material to be crushed passes, a hull board, the lower end of which regulates the size of an opening past the saw cylinder, and means for forcibly projecting cotton at the lower end of the hull board into contact with the saw cylinder.

9. A cotton extracting and cleaning machine comprising a saw cylinder, a pod expeller, a crushing roll located adjacent to said pod expeller, a stationary guard located adjacent to the crushing roll, and between which and said roll the material to be crushed passes, a hull board, the lower end of which regulates the size of an opening past the saw cylinder, and means for forcibly projecting cotton at the lower end of the hull board into contact with the saw cylinder.

10. A cotton extracting and cleaning machine comprising crushing and feeding mechanism, a saw cylinder, a pod expeller co-operating therewith, a supplemental crushing roll located adjacent to the pod expeller, a stationary circular bar located adjacent to the supplemental crushing roll and extending parallel therewith, a hull board, the lower end of which regulates the size of an opening past the saw cylinder, and means for forcibly projecting cotton at the lower end of the hull board into contact with the saw cylinder.

11. A cotton extracting and cleaning machine comprising a saw cylinder and a hull board, the lower end of which is adapted to vibrate toward and from the saw cylinder

and regulates the size of an uninterrupted opening past the saw cylinder for the escape of hulls.

12. A cotton extracting and cleaning machine comprising a saw cylinder, a hull board, the lower end of which is adapted to vibrate toward and from the saw cylinder and regulates the size of an uninterrupted opening past the saw cylinder for the escape of hulls, and means for continuously vibrating said hull board.

13. A cotton extracting and cleaning machine comprising a saw cylinder, a hull board having spring fingers, the lower end of which are adapted to vibrate toward and from the saw cylinder and regulate the size of an uninterrupted opening past the saw cylinder for the escape of hulls, and means for continuously vibrating said hull board.

14. A cotton extracting and cleaning machine comprising a saw cylinder, a hull board, the lower end of which regulates the size of an opening past the saw cylinder, said hull board comprising a pivoted member, a series of spring fingers secured thereto and forming the hull board proper, an arm secured to said members, and an agitator adapted to rotate in contact with said arm whereby to vibrate said spring fingers.

In testimony whereof, I have hereunto set my hand in presence of two subscribing witnesses.
